UNITED STATES PATENT OFFICE.

LINCOLN H. CLEMENTS, OF CLEMENTS, MINNESOTA.

UNLOADING AND EXCAVATING MACHINE.

Application filed March 12, 1923. Serial No. 624,450.

To all whom it may concern:

Be it known that I, LINCOLN H. CLEMENTS, a citizen of the United States, residing at Clements, in the county of Redwood 5 and State of Minnesota, have invented certain new and useful Improvements in Unloading and Excavating Machines, of which the following is a specification.

This invention relates to machines for excavating, and for unloading gravel, sand, coal or the like from gondolas or other freight cars and delivering it into motor-trucks, wagons or other vehicles, for transportation to other points, and the main object is to provide a practical, efficient and easily operated machine for such purposes. Further objects will be disclosed in the course of the following specification, are particularly pointed out in the appended 20 claims, and are clearly illustrated in the accompanying drawings, wherein:

Fig. 1 is a side elevation of the machine, showing, adjacent thereto, a fractional section of a car to be unloaded.

Fig. 2 is an end view of the machine, with the lower portion thereof broken away.

Fig. 3 is a horizontal sectional detail on the line 3—3 in Fig. 2.

Fig. 4 is an enlarged section on the line 30 4—4 in Fig. 2.

Reference will now be made to the various elements of the structure by reference characters, like parts being indicated by like characters throughout the various figures of 35 the drawings.

The base A of the machine is preferably mounted on a vehicle, so as to be portable, and in the present instance is centrally pivoted on a vertical spindle B of a truck C, 40 so that it can be turned or swung to any desired position. The base is further provided with an annular series of casters or rollers D, which roll on a circular track E of the truck platform F. A heavy coil 45 spring G is preferably interposed between the base A and a nut or head H on the upper end of the spindle, so that the base A will be yieldingly yet firmly held down on the track E at all times.

At what will hereinafter be termed the front of the base A, is secured a pair of upright standards 5, to which are pivotally secured the rear ends of a pair of radius bars 6, adapted to swing in vertical planes.

To the outer or front ends of the radius bars 6 is secured a conveyor 7, having shafts

8 and 9 which carry endless chains 10 having buckets 11. Angle iron tracks 12 are preferably used to support and guide the chains 10.

A shaft 13 is journaled in the conveyor and is driven with a chain 14 by a shaft 15, which is journaled in a hollow shaft or pipe 16, carrying the radius bars 6. The shaft 15 has a pulley 17 driven by a belt 18 from the pulley 19 of an engine 20, on the base A. The opposite end of the shaft 13 has a sprocket gear 21, driving a sprocket chain 22 which passes over a sprocket gear 23 fixed on the shaft 8; thus transmitting the power of the engine 20 to the carrier chains 10.

A hood 24 is provided over the top run of the buckets 11, and suitable handles 25 are secured near the lower end of the conveyor, to facilitate its being swung or moved, as desired.

The shaft 8 is journaled in adjustable plates 26, secured by screws 27 and adjusted by bolts 28, so that the chains carried thereon can be slightly lengthened or shortened to regulate their slack.

To the plates 26 is rigidly secured a primary or receiving chute 29, to which is pivotally secured, as at 30, the upper end of a long delivering chute 31 (see Fig. 1), having a gate 32 at its lower end. The delivering end of the chute 31 is made vertically adjustable, by being carried by a rope 33, which passes over a pulley 34 and is secured as at a hitch 35, arranged on an upright frame or support 36.

The vertical adjusting of the conveyor 7 is accomplished by a crank 37 on a shaft 38, which shaft projects out far enough so that the crank clears the belt 18. The shaft 38 is journaled on the uprights 5, and is provided with a pinion 39, which meshes with and drives a gear 40 on a shaft 41, also journaled on the standards 5. A hand releasable dog 42 is arranged to engage the gear 40, to prevent it from turning after the position of the conveyor is determined. The shaft 41 is provided with spools or small drums 43, on which are wound the lower ends of cables 44. These cables pass over fixed pulleys 45, and moving pulleys 45^a (at the outer ends of the bars 6, the upper ends being secured, as at 46, to the standards 5).

Pivotally secured between the standards 5, as at 47, is a short return chute 48, adapted to catch all the material dropped from the

upper end of the conveyor and not received by the chute 29, and return it to the car which is being unloaded. The lower end of this chute is supported on a substantially 5 U-shaped bracket 49 which is selectively secured, at its lower ends, in perforations 50 of plates 51, on the standard 5, thus enabling the chute to be readily adjusted to any angle desired.

10 It is understood that suitable modifications may be made in the general design and structural details of this invention, provided, however, that such modifications come within the spirit and scope of the appended 15 claims.

Having now therefore fully shown and described my invention what I claim to be new and desire to protect by United States Letters Patent is:

20 1. The combination in a machine of the

character described, of a conveyor adapted to carry material from a car to a higher elevation, an inclined chute arranged with its upper end to receive such material from the conveyor, and a return chute adjustably arranged vertically below the upper end of said conveyor to receive spilled material therefrom and return it back to the car. 25

2. The combination in a machine of the class described, of a conveyor adapted to 30 carry material from a car to a higher elevation, an inclined chute arranged with its upper end to receive such material from the conveyor, an inclined return chute arranged to receive spilled material and return it back 35 to the car, and means for vertically adjusting the delivery end of the return chute.

In testimony whereof I affix my signature.

LINCOLN H. CLEMENTS.
